UNITED STATES PATENT OFFICE.

GEORGE HENRY WRIGHT, OF SPOKANE, WASHINGTON.

IMPLEMENT FOR APPLYING AND CLENCHING FENCE-WIRE CLAMPS.

SPECIFICATION forming part of Letters Patent No. 727,527, dated May 5, 1903.

Application filed April 28, 1902. Serial No. 105,004. (No model.)

To all whom it may concern:

Be it known that I, GEORGE HENRY WRIGHT, a citizen of the United States, and a resident of Spokane, in the county of Spokane and State of Washington, have invented new and useful Improvements in Implements for Applying and Clenching Fence-Wire Clamps, of which the following is a full, clear, and exact description.

- 10 My invention relates to implements or tools especially adapted to the work of applying and clenching sheet-metal fasteners or clamps to the crossing wires of fences or the like; and one object that I have in view is the provision of a simple, compact, and efficient device which may be operated easily and quickly to bend or clench the fastener around the wires and to bend the wires themselves at the point of intersection.
- 20 A further object is to so construct the parts forming the tool that the clamp or fastener may easily be placed in the tool, and by a slight movement of the bending-jaws the said clamp or fastener is seized by said jaws, so as to be securely held in the implement, thus enabling the clamp to be brought by the implement into position adjacent to the wires for attachment thereto by the subsequent operation of said implement.
- 30 A further object is the provision of novel forms of bending-jaws adapted to not only seize the clamp, but to bend or tuck parts of the latter around the wire at the beginning of the closing movement of the jaws.
- 35 A further object is to provide the implement with means for holding it against relative displacement on the wires during the operation of bending the clamp by the closing movement of the jaws, said holding means being adapted for engagement with a line-wire and being operable with the jaws, so as to open for the ready application of the implement to the line-wire.
- 45 With these ends in view the invention consists in the combination, construction, and arrangement of parts, which will be herein-after fully described, and the actual scope of the invention will be defined by the claims.
- 50 Reference is to be had to the accompanying drawings, forming a part of this specification, in which similar characters of reference indicate corresponding parts in all the figures.

Figure 1 is a perspective view of an implement or tool for clenching a clamp or fastener to the meeting wires of a fence as contemplated by the present invention. Fig. 2 is a side elevation of the implement with the jaws in an open position. Fig. 3 is a front elevation of the implement with its parts in the position shown by Fig. 2. Fig. 4 is another side elevation with the jaws in the closed position. Fig. 5 is a transverse sectional view taken through the anvil-block in the plane of one of the rocking bolts, to be hereinafter more fully described, the plane of the section 65 being indicated by the dotted line 55 of Fig. 2. Fig. 6 is a side elevation of my improved implement, illustrating a clamp or fastener in position to be bent by the jaws thereof; and Fig. 7 is a detail perspective view of the 70 fastener applied to the crossing wires of a fence.

5 designates an anvil-block, which is made of a single solid piece of steel or any other suitable material. This block is recessed at 75 its diagonally opposite corners, as indicated at 6 6^a in Fig. 3, and the block is further provided with the longitudinal cavity or socket 7 and with the notches 8 9. The cavity or socket 7 extends across the transverse center 80 of the anvil-block, and the end portions of this cavity overlap the inner ends of the recesses 6 6^a. The notches 8 9 are disposed on opposite sides of the longitudinal axis of the cavity or socket 7, and said notches lie adjacent to the inner closed ends of the recesses 6 6^a, all as will be more clearly understood by reference to Figs. 1 and 3.

10 and 11 designate the rocking bolts or arbors, which are loosely fitted in opposite end 90 portions of the anvil-block, so that one arbor will extend through one of the recessed or cut-out portions of the block.

12 13 designate bending-jaws, which are made integral with the arms 12^a and 13^a, respectively, said arms forming the handles or levers of the implement. The bending-jaws are made fast with the rocking bolts or arbors 10 11, respectively, and this end is attained by providing each arbor with a polygonal 100 shouldered portion 14, adapted to fit into a correspondingly-shaped opening 15, which is provided in one of the jaws. The bending-jaws or their arms are fitted in the recessed

portions 6 6^a of the anvil-block, so that the jaws will be pivotally connected to the diagonally opposite corners of said anvil-block, and the jaws are curved, as shown by Figs. 5, 1, 2, and 4, so as to face or extend inwardly toward each other. Each jaw is provided with a curved or overhanging portion which forms a beak 16, and in the free extremity of this beak is produced a notch 17. The notched beaks of the two jaws lie in opposing relation to the notched side portions 8 and 9 of the anvil-block, and said jaws when closed are adapted to traverse or move across the notched portions of the anvil-block. Said notched portions of the anvil-block constitute the seats for the side wings and the lips of the clamp or fastener which is adapted to be set by the operation of the improved implement; but I have not considered it necessary to show this clamp or fastener in the present application, because it constitutes the subject-matter of a separate application filed by me on the 12th day of March, 1902, serially numbered 97,831.

25 In the operation of applying the clamp or fastener to the crossing wires of a fence I have found it desirable to provide the implement with some means which are adapted to engage with the line-wire, so as to assist in holding the implement in proper position relative to said line-wire during the clenching of the fastener by the closing movement of the jaws. Obviously the tool holding or retaining means should be capable of operation so as to readily open for adjustment or application to the line-wire, and I have therefore provided a pair of holding-jaws which are movable with the bending-jaws and are adapted to engage with the line-wire in advance of the bending of the fastener around the crossing wires. These holding or retaining jaws are indicated by the numerals 18 19, and they are mounted on the rocking bolts or arbors 10 11, respectively. The jaws are provided with angular or polygonal openings 20, adapted to receive the correspondingly-shaped angular portions 21 of the bolts or arbors, and thus the retaining-jaws are made fast with the respective bolts, so as to turn with the bending-jaws when the handles are opened and closed. The jaw 18 is disposed on the opposite side of the anvil-block 5 from the bending-jaw 12, although these two jaws are made fast with the bolt 10, which serves to pivotally connect said jaws 12 18 to one end portion of said anvil-block. The other retaining-jaw 19 is disposed on the opposite side of the anvil-block from the bending-jaw 13, and these two jaws 13 19 are connected to an end portion of the anvil-block by the same bolt or arbor 11. From this description it will be apparent that the bending-jaws lie at diagonally opposite corners of the anvil-block and the retaining-jaws are similarly disposed 65 at the remaining corners of the anvil-block, the relative arrangement of the parts being more clearly indicated by Figs. 1 and 3.

The retaining-jaws 18 19 have their ends extended beyond the notched beaks of the bending-jaws on the pair of arbors, and the relative position of the retaining-jaws to the bending-jaws is indicated more clearly by Figs. 2 and 4, from which it will be seen that the extremities of the jaws 18 19 project in advance of the notched ends of the bending-jaws, so that the retaining-jaws will engage with the line-wires before the bending-jaws will engage with the clamp during the operation of the implement.

The retaining-jaws 18 19 are offset from the solid or non-recessed corners of the anvil-block, so that they will occupy positions out of line with the bending-jaws, which lie in opposing relation thereto, this offset position of the retaining-jaws being shown more clearly by Fig. 3. Any suitable construction may be adopted in order to secure this disalignment in the relation of the retaining-jaws to the bending-jaws; but, as shown by the drawings, the retaining-jaws are provided with the enlargements 22, which lie next to the side faces of the anvil-block. It is evident that suitable washers may be employed or that the side faces of the anvil-block may be offset, the same forming an equivalent construction.

95 As shown by the drawings, each bolt or arbor 10 or 11 has two polygonal or angular portions and an integral head portion. The round part of the bolt or arbor extends through the anvil-block, whereas the angular portions 100 14 21 lie on opposite sides of the anvil-block in order to receive the bending-jaw and the retaining-jaw, and, finally, the headed portion of the bolt or arbor lies against the bending-jaw, while the threaded extremity of the 105 bolt receives the nut adapted to bind against the retaining-jaw. (See Fig. 5.)

I prefer to equip the implement with means for guiding the handles and jaws in their opening and closing movements. A suitable form 110 of construction for this purpose is the curved arm 23, which is made fast with one of the handles and is provided with a longitudinal slot 24, adapted to receive the guide-stud 25, the latter being secured firmly to the other 115 handle of the implement.

In operation the jaws are opened to assume the positions shown by Figs. 1, 2, and 3 by spreading the handles, and the clamp or fastener A is placed against the anvil-block in 120 order that the body portion of the clamp will occupy the recess or socket 7, while the side wings or lips of the clamp will fit in or to the seats afforded by the notches 8 9. In placing the clamp A in the implement the jaws 12 13 125 should be closed slightly in order that the notches 17 in the beaks of said bending-jaws will engage with the outwardly-extending lips a of the clamp, as shown by Fig. 7, whereby the bending-jaws are adapted to confine the 130 clamp against the face of the anvil-block and the implement may easily be placed in position, with the clamp attached thereto. Having fitted the fastener to the jaws and anvil-

block of the tool, the operator now brings the parts into position opposite to the crossing wires of the fence, the line-wire passing through the space between the jaws 12 13 and the other pair of jaws 18 19, said wire extending across that part of the fastener which occupies the seats 8 9. In closing the handles of the tool the retaining-jaws 18 19 move in advance of the notched beaks of the bending-jaws, because the bolts or arbors 10 11 are turned by the movement of the handles, and thus the retaining-jaws will engage with the line-wire in a manner to prevent accidental displacement of the implement during the operation of bending the parts of the clamp around the crossing wires. At the same time that the handles are closed together, so as to make the retaining-jaws close upon the line-wire, the bending-jaws 12 13 become active for the purpose of forcing the outwardly-extending portions of the clamp or fastening around the line-wire, and the clamp is so forcibly applied to the wires that the line and stay wires will become bent and interlocked at their points of intersection simultaneously with the application of the fastener thereto. After the operation of bending the fastener shall have been completed the handles are opened and the arbors are rocked, thereby spreading the two pairs of jaws, so as to disengage the retaining-jaws from the line-wire and the bending-jaws from the attached fastener, thus permitting the implement to be easily withdrawn from the work.

In Fig. 7 of the drawings I have shown the clamp A applied to the crossing wires B C of a fence. This clamp, as hereinbefore indicated, consists of a body portion and two arms or lips, said body portion engaging with one of the wires, as B, while the arms or lips a a are bent or doubled around the intersecting wire C.

Having thus described my invention, I claim as new and desire to secure by Letters Patent—

1. An implement of the class described, comprising an anvil-block provided with a cavity and with seats on opposite sides of said cavity, bending-jaws on said anvil-block at the diagonally opposite corners thereof and arranged to traverse the seats thereon, and retaining-jaws movable with said bending-jaws relatively to the anvil-block.

2. An implement of the class described, comprising an anvil-block having a cavity and seats disposed on opposite sides of the cavity, and bending-jaws pivoted to said anvil-block at diagonally opposite corners there-

of, and disposed in facing relation and arranged to traverse the seats on said block.

3. An implement of the class described, comprising an anvil-block having recesses in its diagonally opposite corners and a cavity which is disposed in overlapping relation to said recesses, and bending-jaws fulcrumed in said recessed portions of the anvil-block.

4. An implement of the class described, comprising an anvil-block having recesses, a cavity and seats adjacent to said recesses and on opposite sides of the cavity, and bending-jaws disposed in the recessed portions of the anvil-block and arranged to traverse the seats thereof.

5. An implement of the class described, comprising an anvil-block, suitable bending-jaws attached thereto, and movable retaining-jaws actuated by the opening and closing movements of said bending-jaws.

6. An implement of the class described, comprising an anvil-block, bending-jaws attached thereto, and retaining-jaws movable with said bending-jaws, and having their active ends disposed in advance of the corresponding ends of the bending-jaws.

7. An implement of the class described, having an anvil-block, bending-jaws provided with notched free ends and connected to said anvil-block so as to lie in opposing relation, and movable retaining-jaws disaligned relative to the bending-jaws and actuated by the opening and closing movements thereof.

8. An implement of the class described, comprising an anvil-block, rocking arbors mounted in said block, bending-jaws having handles and attached to the respective arbors to turn the latter, and retaining-jaws attached to the arbors for actuation thereby.

9. An implement of the class described, comprising an anvil-block having recesses in its diagonally opposite corners, arbors extending through said recessed portions of the anvil-block, bending-jaws having handles and connected to said arbors to turn the latter, and retaining-jaws attached to said arbors and disposed opposite to the unbroken corners of the anvil-block, said retaining-jaws being offset relative to the anvil-block, and disposed in disaligned relation to the bending-jaws.

In testimony whereof I have signed my name to this specification in the presence of two subscribing witnesses.

GEORGE HENRY WRIGHT.
